CLAIM

The ornamental design for a high-power light emitting diode chip, as shown and described.

DESCRIPTION

FIG. 1 is a perspective view of a high-power light emitting diode chip showing our new design;

FIG. 2 is a front side view of the embodiment shown in FIG. 1;

FIG. 3 is a back side view of the embodiment shown in FIG. 1;

FIG. 4 is a left side view of the embodiment shown in FIG. 1; FIG. 5 is a right side view of the embodiment shown in FIG. 1;

FIG. 6 is a top view of the embodiment shown in FIG. 1; and, FIG. 7 is a bottom view of the embodiment shown in FIG. 1.
